UNITED STATES PATENT OFFICE.

JOHN CUTHEBERT, OF CHICAGO, ILLINOIS, ASSIGNOR, BY MESNE ASSIGNMENTS, TO ECONOMY FUSE AND MANUFACTURING COMPANY, OF CHICAGO, ILLINOIS, A CORPORATION OF NEW YORK.

LAMP SOCKET.

Application filed December 4, 1916. Serial No. 135,050.

To all whom it may concern:

Be it known that I, JOHN CUTHEBERT, a citizen of the United States, residing at Chicago, in the county of Cook and State of Illinois, have invented certain new and useful Improvements in Lamp Sockets, of which the following is a specification.

My invention relates to improvements in lamp sockets and has especial reference to means for securing the mechanism thereof to the enclosing shell, or casing and for securing the latter to a socket-supporting fixture.

One of the objects of my invention is to provide an improved socket and attaching means, as hereinafter more fully explained.

Other, further and more specific objects of my invention will become apparent from the following description when taken in conjunction with the drawings, wherein:—

Fig. 1 is a side elevation of the socket showing it attached to a socket-supporting fixture.

Fig. 2 is an enlarged, central section taken on line 2—2 of Fig. 3.

Fig. 3 is a transverse section taken on line 3—3 of Fig. 2.

Fig. 4 is a broken-away part of the upper end of the shell and attaching member.

Fig. 5 is a section taken on line 6—6 of Fig. 2 before the attaching means is clamped on the fixture.

Fig. 6 is a similar view showing the clamp-operating ring turned to the proper degree to secure the shell to the fixture.

Fig. 7 is a preferred form of the fixture clamping device.

In all the views the same reference characters are employed to indicate similar parts.

The socket, shown in the drawings, is of the keyless type. It is arranged so that it may conveniently be attached to the conducting wires, without removing the enclosing shell, simply by passing the wires into the open, lamp-engaging end from the socket attaching end, and coiling the wires around the shanks of the respective clamping screws and subsequently clamping the eyes thus formed, to the socket terminals.

This may quickly be accomplished by introducing a screw driver into the open end of the socket and rotating the binding screws. Then the shell and enclosed parts may be attached as efficiently to the socket-

supporting fixture by an improved means 55 that does not require material rotation of the socket, after the wires are attached thereto.

When the shell of the socket is inseparably secured to the enclosed parts, and the 60 socket is to be attached to the fixture, after the wires have been placed in the said fixture, it is disastrous to the wires to rotate the sockets sufficiently to screw it home on the threaded end of the fixture. Besides, 65 such a procedure, including disassembling and reassembling of the socket parts, requires an unnecessarily, relatively long period of time, thus undesirably increasing the cost of installation.

In the structure, which I have disclosed in the accompanying drawings, I reduce the cost of manufacture to the minimum by making the casing shell in one piece and inseparably securing it to the enclosed parts 75 and furthermore I have provided a socket that may be installed by the expenditure of the smallest possible time required to secure the conducting wires thereto and to fix the socket upon the fixture.

In the embodiment illustrated 10 is a fixture, such as the threaded end of a pipe or bracket, to which the socket is to be attached. Fixed to the end of the pipe 10, is a threaded sleeve 11, the threaded end 12 85 being adapted for screw threaded association with the socket. Above the threads 12 is a shoulder 13 against which the outer end of the threaded nipple, or clamping sleeve 14, abuts when it is in place. The attaching sleeve or member 14, which is secured to or a part of the shell 15 of the socket, as shown at 16, is preferably, a continuous sleeve, at the point of attachment, but is divided into clamping members 14^a and 14^b, which are 95 segmental in form,—as more clearly shown in Figs. 5 and 6—provided by cutting away diametrically opposite portions of the member 14, in flat planes, as shown at 17 and 18, thus cutting entirely thru the thread, 100 provided on the inside of the member 14, and permitting the opposite clamping members 14^a and 14^b to be separated, one from the other, to a greater distance than their original diameter, as shown in Fig. 4. An 105 unthreaded clamp-operating cam ring 20, having opposite inward depressions 21—21, is slipped over the member 14. The dia-

22

ter of the ring 20 is sufficiently large to permit the clamps 14^a and 14^b of the member 14 to freely slip over the threaded end 12 of the nipple 11, in placing the socket in position on the fixture, as the indentations 21—21, of the ring 20, are then within the space provided by the cutaway side portions 17 and 18 of the member 14. When the cam ring 20 is rotated, about 90°, so that the indentations 21—21 are moved, from the positions shown in Fig. 5 to the positions shown in Fig. 6, they press inwardly the clamping members 14^a and 14^b so that the internal threads thereof make engagement 15 with the external threads 12 of the nipple 11, thus holding the socket in place, as clearly shown in Fig. 2. In placing the socket on the fixture 10, the conducting wires are prepared and threaded thru the base, the ring 20 being freely rotatable over the members 14^a and 14^b, at which time the member 14 is slipped axially onto the threaded end of the nipple 11; then, by means of gas pliers, or the like, the cam ring 20 is rotated, about 90 degrees, when the projections 21—21, on opposite sides, will ride upon the cam portions of the members 14^a and 14^b, of larger diameter, thus pressing these members laterally into intimate contact 25 with the threaded end of the nipple 11, after which a very slight rotation of the socket shell 15 will cause the upper ends of the member 14 to make intimate contact with the shoulder 13 of the fixture, thus quickly 30 and effectually securing the socket firmly in place on the fixture.

The insulating base portion 22, upon which the terminal clamping screws 23 and 24 are mounted, is provided with tapered, 40 axially-extending openings 25 and 26, through which to pass the conducting wires 27 and 28. The plate 29 is segmental in shape and is held in place by screws 30 passing thru the insulating block, or base 22, and to which plate is secured the lamp-engaging screw-shell 31. The plate 29 is perforated, as at 32, in register with the perforation 25 thru which the wire 27 is passed and the binding screw 23, which is capable 45 of twisting the wire around the shank, and subsequently clamping it in place, is preferably threaded in the plate 29, engages the wire when rotated, as clearly shown in Fig. 2, which may be accomplished by inserting 50 a screw driver thru the open end of the shell 31. Another plate 33 has an opening 34, which is in register with the opening 26 of the base member 22, thru which to thread the wire 28 for engagement with the terminal screw 24, whereby the screw 24 first coils 55 the wire around its shank and subsequently clamps it to the plate 33, by operation of a screw driver inserted thru the shell 31.

Secured under the plate 33 is a spring 60 clip 35, which is held in place by a screw or

rivet 36, insertable thru the base member 22. The spring clip 35 serves as a central contact for the socket. Overlying the screw shell 31 and located between the screw shell 31 and the outer shell or casing 15 is an insulating shell 37. The shell 37 extends over the screw-shell 31, and between the screw-shell and the outer shell, or casing 15, and is secured in place, in association with the base portion 22, by means of the plates 29 and 33. The outer casing 15 is secured to the base 22 and to the lining 37, by a coating 38 of cement or glue, preferably such that may be hardened by heat, as liquid bakelite. The outer shell 80 15 is thus firmly cemented to the inner portions of the socket to hold them in place, and as my structure is such that the necessity for removing the shell 15 is no longer present, owing to the fact that the socket 85 may be wired by introduction of a screw driver into the open end thereof for manipulation of the terminal screws which have the quality of twisting the wire around their shanks and then clamping it, 90 it is not necessary to remove the shell, and the time required to fix the socket to the conducting wires and fixtures is thus materially reduced.

In Fig. 7 I have shown the fixture clamping member 14 as an integral part of the shell 15 and the clamping ring 20 inseparable from said clamping members but freely rotatable thereon. The upper ends of the members 14^a and 14^b are expanded 100 outwardly after the ring 20 is placed over the members. This permits the ring to freely rotate but prevents its removal.

It is of course manifest to persons skilled in the art that a socket made after the general plan in which a key or switch is included as a part of the structure may have its shell fixed to the enclosed parts in the same manner and may be capable of being connected to the socket-supporting fixture 110 by the same means herein disclosed.

While I have herein shown a single embodiment of my invention, for the purpose of clear disclosure, it will be manifest that many changes may be made in the configuration and disposition of the parts with- 115 in the scope of the appended claims.

Having described my invention, what I claim is:—

1. In combination with an enclosing shell, 120 of a lamp socket; an internally-threaded sleeve, or member secured to the shell, and circumferentially divided for clamping attachment to a fixture and a ring surrounding said clamping member, having an inwardly-projecting part to clamp the member on the fixture when the ring is rotated on its support.
2. In combination with an enclosing shell 125 of a lamp socket; an internally-threaded 130

sleeve, or member secured to the shell having part of its periphery cut away and thus attenuated or divided thru the thin wall thus provided, for clamping attachment to a fixture having an exterior threaded end, and a ring surrounding said member, having an inwardly-projecting part to be contained within the cut-away space, to clamp the members on the fixture when the ring is 10 rotated on its support.

3. A lamp socket structure comprising an insulating base; wire terminals mounted therein; a lamp-engaging screw-shell, carried by the base; an insulating jacket, surrounding said screw-shell; a one-piece enclosing shell having a two-part, internally-threaded member for clamping attachment to a threaded fixture, and a rotatable clamping cam, surrounding said two-part member 20 to force said members laterally into clamping relation with said fixtures.

4. A lamp socket structure comprising an

insulating base; wire terminals mounted thereon; a lamp-engaging screw-shell carried by the base; an insulating jacket surrounding said screw-shell; an enclosing shell having a plural clamping member, comprising an internally threaded sleeve divided by cutting away the wall of the sleeve in tangential planes to provide a contractible clamping member for attachment to a threaded fixture, and a rotatable clamping member, having an internal projection normally resting in the space produced by the cut-away portion of said clamping member, to force said clamping members into clamping relation with said fixture.

In testimony whereof I hereunto set my hand in the presence of two subscribing witnesses.

JOHN CUTHBERT.
